PAINTBRUSH HANDLE OR THE LIKE

John W. McGuire, Neponsit, N.Y., assignor to Baker Brush Co., Inc., New York, N.Y., a corporation of New York

Filed Sept. 16, 1968, Ser. No. 13,541

Term of patent 14 years

Int. Cl. D4—04

U.S. Cl. D4—38

FIGURE 1 is a plan view of one face of a paintbrush handle or the like, showing the novel design, the opposite face thereof being identical;

The broken line showing of the bristle portion is for illustrative purposes only.

I claim:

The ornamental design for a paintbrush handle or the like, substantially as shown and described.
